BALL-PLAYER'S TRAINING DEVICE

Robert V. Fessler, Indianapolis, Ind.

Application November 27, 1946, Serial No. 712,532

20 Claims. (Cl. 273—26)

1

The present invention relates to a ball player's training device, and more particularly to a target mechanism so constructed and designed as to reveal to a baseball player aberrations in his batting swing. It is a primary object of the invention to provide means for training a baseball player to swing his bat in a flat, horizontal path, and to meet the ball squarely with his bat. It is a further object of the invention to provide means whereby a player may perceive any tendency to swing his bat out of a horizontal plane and may perceive whether his bat is moving upwardly or downwardly as it meets a target, representing a baseball. A further object of the invention is to provide such a device so constructed as to withstand the terrific blows which are dealt to it in practice, without serious deteriorations, and to provide means whereby any part of the device which is subjected to particularly severe punishment, and so becomes worn, may be replaced without disturbing other similar parts which have not become so worn.

A still further object of the invention is to provide a device of the character above-described which may be successfully used by players of varying heights, and to practice swings at various levels within the range of a pitched strike.

A still further object of the invention is to provide means to indicate to a player whether or not the blow which he has delivered against the practice device has been sufficiently square and forceful to have produced a long, fair hit in a real baseball game. It is a further object of the invention to provide signaling means which will signal a square, forceful blow, but which will be substantially unaffected by a blow which meets the target at an angle varying materially from perpendicularity.

A further object of the invention is to provide, in a device of the character under consideration, specific structural features providing for ready repair and replacement of any worn or broken parts, so that the mechanism need not be out of service for a material length of time in case of wear or breakage of any part thereof.

Still further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

2

Fig. 1 is a perspective view of a device constructed in accordance with my invention;

Fig. 2 is an enlarged, fragmental perspective, taken from a different angle, and showing further details of construction of such device; and

Fig. 3 is an enlarged, fragmental elevation of a part of the standard and a part of one of the guard elements of my invention, parts being shown in section for clarity of illustration.

It is recognized that a baseball player's batting swing should carry his bat through an arc substantially entirely located in a horizontal plane, and that it is essential, in order for the player to get a long and speedily driven ball, that at least a few inches of the path of the bat just before the bat meets the ball, and a few inches of that path just after the bat meets the ball, must be in such a horizontal plane, and must not have any vertical component. Too many players use a swing in which the free end of the bat moves downwardly from above the level of the player's shoulders approximately to the point where the player expects his bat to meet the ball, and thereafter moves upwardly. Such a swing is conducive to complete misses if the speed of the ball or the speed of the bat is misjudged to any material extent, and will frequently result in driving the ball downwardly onto the ground or upwardly in a pop fly.

I have devised means comprising a plurality of targets arranged at varying levels above the ground or floor, each target being guarded, above and below the same by horizontally projecting guard elements extending forwardly beyond the target area a distance at least equal to twice the diameter of a standard baseball, and preferably somewhat farther. The guard means are spaced apart a distance only slightly greater than the diameter of a standard baseball. As a result, a player using a swing having any material vertical component and attempting to strike the target will strike, instead, the guard element above or below the target, and the degree of deviation of his swing from a true horizontal plane will determine the distance from the target area at which his bat will strike one or the other of the guard elements.

Referring more particularly to the drawings, it will be seen that I have illustrated a standard 10 which may preferably comprise a hardwood post four inches by six inches in transverse dimensions. One of the four inch faces 11 of the standard is provided with cushioning means which may be of almost any desired character capable of absorbing the shock of a baseball bat

blow, without stinging the player's hands. I have shown cushioning means comprising a plurality of separate blocks 12 of rubber, which may be foamed rubber or solid rubber, or which may be made of any of the various synthetic rubbers, though I prefer foamed natural rubber. Associated with each block 12 is a strap 13 of corded and vulcanized fabric provided, substantially at its midpoint, with a target 14 preferably comprising an integral white disc having a diameter equal to that of a standard baseball. Each strap 13 is associated with its respective cushioning block with the target 14 located at the center of the forward face of the block and with the ends 15 of the strap extending along the lateral edges of the cushioning block and into contact with the lateral faces of the standard 10, to which they are secured by a plurality of screws 16. Preferably, the strap ends will be stamped with perforations for the reception of the screws 16, which are passed through said perforations and then turned into the body of the standard 10, as shown. This arrangement makes it easy to remove any individual strap 13 and/or its associated block 12, and to replace the same, without disturbing the component parts of any of the other target devices.

Inflated bags, or bags filled with fluent material, might be used in place of the blocks 12; but it is my present belief that the best results can be obtained with the rubber blocks illustrated.

Preferably, each block 12 will be notched at its lower end, as at 17, and at its upper end, as at 18, for the accommodation of guard elements 19.

At levels spaced above and below the center of each block 12, I prefer to form sockets 20 in the forward face 11 of the standard. Penetrating the standard from back to front at the center of each such socket is a bore 21 in which may be mounted a bolt 22, the threaded end of said bolt projecting into a socket 23 formed in the rear face of the standard 10, and there receiving a nut 24 preferably bearing against a washer 25 whereby said bolt may be drawn up tightly upon the standard 10. The head 26 of the bolt 22 is gripped in the reduced end of a coiled spring 27 which is at least covered with vulcanized rubber, or similar material. Preferably, I will cast a block 28 of rubber upon and about each spring 27 and the associated head 26 of its bolt 22, in the manner clearly illustrated in Fig. 3. Such an arrangement somewhat reduces the flexibility of the guard member 19, while leaving it sufficiently flexible to receive, without substantial damage, accidental blows delivered against it by practicing batters.

It will be seen that, in order for a practicing batter to deliver a square blow against a target 14, his swing must be flatly horizontal as his bat enters squarely and accurately between the guard elements 19 positioned immediately above and below the selected target area 14. As is clearly to be seen from an inspection of Fig. 1, the guard elements associated with each target area are spaced apart a distance only slightly greater than the diameter of a standard baseball.

Preferably, but not absolutely necessarily, the standard 10 will be braced by struts 29, 29 secured to the upper end of the standard and inclining outwardly and downwardly therefrom to anchorages upon posts 30, 30. I prefer to insert a turnbuckle 31 in each strut 29 in order to facilitate the mounting of the assembly.

The device as thus far described is completely

operative to assist in the training of baseball players; but added interest can be provided by arranging the mechanism so that an audible or visible signal will be actuated when, and only when, a true, square, forceful blow is delivered accurately against the center of a selected target. To that end, I mount a signal and signal-actuating mechanism upon a plate or carrier 32 readily removably secured to that face of the standard 10 opposite the forward face thereof. Preferably, said plate will be formed with openings registering with lag screws 33 or the like embedded in the rear face of the standard 10, and wing nuts 34, cooperable with the protruding portions of said lag screws, may be turned down to fasten said carrier firmly to the standard.

Supported in vertically spaced brackets 35, 35 carried on said plate 32 is a vertical rod 36 upon which is slidably mounted a clapper 37 for cooperation with a bell 38 mounted at a point near the top of the rod 36. The clapper 37 is urged by gravity into engagement with an end 39 of a lever 40 pivotally mounted at 41 upon the carrier 32, so that the lever arm normally supports said clapper 37. A spring 42 preferably has one end secured to the lever arm 39 and its other end anchored at 43 to the carrier 32, as is clearly to be seen in Fig. 2.

At the level of each target area 14, and coaxially therewith, an opening 44 is formed transversely of the standard and the cushioning means, and a pin 45, having a head 46 in contact with the rear surface of the target area of the strap 13, is received in the outer end of that portion of said opening through the cushioning block. A spring 47, likewise received in the opening 44, is interposed between the pin 45 and a second pin 48, likewise disposed in said opening 44, and terminating in an enlarged flat head 49. The carrier 32 is formed with a series of openings 50, each of which registers, when the carrier is secured to the standard, with one of the openings 44.

A ribbon 51, which will preferably be made of spring steel, has its upper end secured to the carrier 32 at a point above the uppermost opening 50, extends downwardly across all of said openings, in association with the open mouths of the openings 44, and carries at its lower end a projection 52 to which is secured one end of a spring 53 whose other end is anchored, at 54, to the carrier 32 at a point below the lowermost of the openings 50. Obviously, the spring 53 resists upward movement of the lower end of the ribbon 51. As is clearly to be seen upon inspection of Fig. 2, the spring 42 resiliently holds the lever arm 39 in engagement with the upper surface of the projection 52.

The ribbon 51 is held in contact with the carrier 32 and with the heads 49 of the pins 48 by means of rollers 55, mounted in brackets 56, 56 on opposite sides of the ribbon and suitably secured to the carrier 32. Adjacent rollers 55 are positioned above and below the point of engagement of each pin 48 with the ribbon 51.

It is to be noted that the actuator assemblies mounted in the openings 44 are laterally and axially yieldable. The lateral yieldability of these assemblies permits distortion thereof if a glancing or poorly directed blow is delivered against any target area 14. If there is any substantial component of that blow which is not normal to the target surface, the pin 45 will be deflected out of the axial line of the actuator assembly, so that a relatively small component of

force will be delivered axially through the pin 48 to the ribbon 51. In such a contingency, the cushioning block 42 is distorted to permit transverse movement of the head 46 of the pin 45, and the small axial component of force delivered through the pin 48 will be insufficient to actuate the signal mechanism.

If, however, a forceful blow is delivered squarely to the center of the target area, substantially all of the force of that blow will be delivered axially through the pin 48 to the ribbon 51, thereby driving that portion of said ribbon engaged by the head 49 of the pin 48 rearwardly and drawing the lower end of said ribbon forcefully upward, through a considerable magnitude of movement, against the tendency of the spring 53. Such movement of the lower end of the ribbon 51 will cause a sudden, forceful swing of the lever arm 39 in a clockwise direction, thereby imparting an upward momentum to the clapper 37, so that a blow of sufficient force will cause the clapper 37 to travel upwardly along the rod 36 until it strikes the bell 38 to signal a good, clean blow delivered against the selected target.

I have found that a tremendous amount of force can thus be transmitted to the clapper 37, so that the bell 38 may be mounted a considerable distance above the lower end of the ribbon 51. In practice, I prefer to mount the bell 38 near the top of the standard, so that a very strong and clean blow must be delivered in order to actuate the signal. However, if desired (for instance, for use in amusement parks and the like), the bell 38 may be mounted near the bottom of the standard, as indicated in Fig. 1.

Other devices may be used for actuating any desired type of signal, but it is essential, to the accomplishment of my intended functions, that the primary actuating means, through which the effect of the batter's blow is transmitted to the signal device shall be of such character that the signal means will not be actuated unless substantially the entire force of the blow is delivered to the target centrally and on a line substantially normal to the target surface.

I claim as my invention:

1. In a device of the character described, a standard, cushioning means on one substantially vertical face of said standard, and guard means projecting substantially horizontally from said face, said guard means being vertically spaced apart a distance only slightly greater than the diameter of a standard baseball.

2. In a device of the character described, a standard, cushioning means on one substantially vertical face of said standard, and guard means projecting substantially horizontally from said face, said guard means being vertically spaced apart a distance only slightly greater than the diameter of a standard baseball, and having an extent from said cushioning means at least twice the diameter of a standard baseball.

3. In a device of the character described, a vertical standard, cushioning means on a substantially vertical face of said standard, said cushioning means being located at a level above the base of said standard between the knees and shoulders of a man standing at the level of said base, having a horizontal dimension slightly greater than the diameter of a standard baseball and having a vertical dimension slightly greater than the diameter of a standard baseball, and guard means projecting horizontally forward from said cushioning means at the upper and lower boundaries of said cushioning means.

4. In a device of the character described, a vertical standard, cushioning means on a substantially vertical face of said standard, said cushioning means being located at a level above the base of said standard between the knees and shoulders of a man standing at the level of said base, having a horizontal dimension slightly greater than the diameter of a standard baseball and having a vertical dimension slightly greater than the diameter of a standard baseball, and yieldable guard means projecting horizontally forward from said cushioning means at the upper and lower boundaries of said cushioning means.

5. In a device of the character described, a vertical standard, cushioning means on a substantially vertical face of said standard, said cushioning means being located at a level above the base of said standard between the knees and shoulders of a man standing at the level of said base, having a horizontal dimension slightly greater than the diameter of a standard baseball and having a vertical dimension slightly greater than the diameter of a standard baseball, and yieldable guard means projecting horizontally forward from said cushioning means at the upper and lower boundaries of said cushioning means, each of said guard means comprising a stiff spring member encased in a tough, yieldable material.

6. In a device of the character described, a vertical standard, cushioning means on a substantially vertical face of said standard, said cushioning means being located at a level above the base of said standard between the knees and shoulders of a man standing at the level of said base, having a horizontal dimension slightly greater than the diameter of a standard baseball and having a vertical dimension slightly greater than the diameter of a standard baseball, and yieldable guard means projecting horizontally forward from said cushioning means at the upper and lower boundaries of said cushioning means, each of said guard means comprising a stiff spring member encased in rubber.

7. In a device of the character described, a vertical standard, cushioning means on a substantially vertical face of said standard, said cushioning means being located at a level above the base of said standard between the knees and shoulders of a man standing at the level of said base, having a horizontal dimension slightly greater than the diameter of a standard baseball and having a vertical dimension slightly greater than the diameter of a standard baseball, and guard means projecting horizontally forward from said cushioning means at the upper and lower boundaries of said cushioning means, each of said guard means comprising a coiled spring bodily enclosed in a block of rubber.

8. In a device of the character described, a vertical standard, cushioning means on one vertical face of said standard and extending from a level below that of the knees of a short man standing on the level of the base of said standard to a level above the shoulders of a tall man standing on the level of said base, means establishing a plurality of visible targets on the forwardly-presented face of said cushioning means, each of said targets having the diameter of a standard baseball, and guard means projecting horizontally forward from said cushioning means above and below each target, adjacent ones of said guard means being vertically

spaced apart a distance only slightly greater than the diameter of a standard baseball.

9. In a device of the character described, a standard, cushioning means on one substantially vertical face of said standard, and guard means projecting substantially horizontally from said face, said guard means being vertically spaced apart a distance only slightly greater than the diameter of a standard baseball, said cushioning means comprising a horizontally resilient element and a covering of tough, rubberized fabric overlying that face of said element remote from said standard, extending past both lateral surfaces of said element, and having its ends fixed to said standard.

10. In a device of the character described, a standard, cushioning means on one substantially vertical face of said standard, and a series of guard members projecting horizontally forwardly from said standard beyond said cushioning means, each of said guard members being vertically spaced from each adjacent guard member a distance only slightly greater than the diameter of a standard baseball, said cushioning means comprising a horizontally resilient element and a strap of tough, rubberized fabric overlying that face of said element remote from said standard, extending past both lateral surfaces of said element, and having its ends fixed to said standard, each of said straps being positioned between a pair of adjacent guard members and being removable from said standard without disturbing any other of said straps.

11. In a device of the character described, a standard, cushioning means on one substantially vertical face of said standard and carrying target means, guard means projecting substantially horizontally from said face beyond said target means and vertically spaced above and below said target means, said guard means being spaced apart a distance only slightly greater than the diameter of a standard baseball, signal means, and means associated with said target means and operable, when said target means is squarely and forcefully struck, to actuate said signal means.

12. In a device of the character described, a standard, cushioning means on one substantially vertical face of said standard and carrying target means, guard means projecting substantially horizontally from said face beyond said target means and vertically spaced above and below said target means, said guard means being spaced apart a distance only slightly greater than the diameter of a standard baseball, signal means carried on said standard, laterally and axially yieldable means horizontally penetrating said standard, and having a portion located at the center of said target means, and means providing an operative connection between said yieldable means and said signal means to actuate said signal means when a blow is squarely and forcefully delivered against said target means.

13. In a device of the character described, a standard, cushioning means on one substantially vertical face of said standard and carrying target means, guard means projecting substantially horizontally from said face beyond said target means and vertically spaced above and below said target means, said guard means being spaced apart a distance only slightly greater than the diameter of a standard baseball, signal means carried on said standard, an element movable to actuate said signal means, a ribbon having one end secured to the face of said standard opposite

the first-named face thereof at a point vertically removed from the level of the center of said target means and extending to a point oppositely vertically removed from said level, spring means anchoring the other end of said ribbon to said standard and resiliently resisting movement of said other end toward said first-named end of said ribbon, laterally and axially yieldable means penetrating said standard and having one end located at the center of said target means and its other end abutting said ribbon intermediate the ends of said ribbon, and means providing an operative connection between the last-named end of said ribbon and said element.

14. In a device of the character described, a standard, cushioning means on one substantially vertical face of said standard and carrying target means, said standard and said cushioning means being formed with a continuous opening therethrough upon an axis substantially normal to the plane of said target, guard means projecting substantially horizontally from said face beyond said target means and vertically spaced above and below said target means, said guard means being spaced apart a distance only slightly greater than the diameter of a standard baseball, signal means carried on said standard, an element movable to actuate said signal means, a ribbon having one end secured to the face of said standard opposite the first-named face thereof at a point vertically removed from said axis, covering that end of said opening remote from said target and extending to a point oppositely vertically removed from said level, spring means anchoring the other end of said ribbon to said standard and resiliently resisting movement of said other end toward said first-named end of said ribbon, a pin reciprocally mounted in said opening and having its outer end located at the center of said target, a second pin reciprocably mounted in said opening with its inner end axially spaced from said first-named pin and its outer end engaging said ribbon, a spring confined between said pins, and means providing an operative connection between the last-named end of said ribbon and said element.

15. In a device of the character described, a standard, cushioning means on one substantially vertical face of said standard and presenting a plurality of vertically-spaced target areas, guard means associated with each target area, and projecting substantially horizontally forwardly beyond said cushioning means above and below each target area, an opening through said standard and cushioning means upon an axis substantially normal to the plane of said one face of said standard and coaxial with the center of each target area, signal means carried on said standard, an element movable to actuate said signal means, a ribbon having one end secured to the face of said standard opposite said one face at a point above the uppermost of said openings and extending across the adjacent open mouths of all of said openings, spring means anchoring the other end of said ribbon to said standard at a point below the lowermost of said openings and resisting upward movement of said other end of said ribbon, laterally and axially yieldable means located in each of said openings, each extending from the center of its associated target area to said ribbon, and means providing an operative connection between the lower end of said ribbon and said element.

16. In a device of the character described, a standard, cushioning means on one substantially

vertical face of said standard and presenting a plurality of vertically-spaced target areas, guard means associated with each target area, and projecting substantially horizontally forwardly beyond said cushioning means above and below each target area, an opening through said standard and cushioning means upon an axis substantially normal to the plane of said one face of said standard and coaxial with the center of each target area, a vertical rod carried adjacent that face of said standard opposite said first-named face, a bell mounted near the upper end of said rod, a clapper slidably mounted on said rod, a ribbon having one end secured to said last-named face of said standard at a point above the uppermost of said openings and extending across the adjacent open mouths of all of said openings near said rod, spring means anchoring the other end of said ribbon to said standard at a point below the lowermost of said openings and resisting upward movement of said other end of said ribbon, laterally and axially yieldable means located in each of said openings, each extending from the center of its associated target area to said ribbon, a lever pivotally carried on the last-named face of said standard and normally supporting said clapper, and means providing an operative connection between said last-named end of said ribbon and said lever to swing said lever upwardly when said last-named ribbon end is moved upwardly.

17. In a device of the character described, a standard, cushioning means on one substantially vertical face of said standard and carrying target means, guard means projecting substantially horizontally from said face beyond said target means and vertically spaced above and below said target means, a carrier, means readily removably securing said carrier to that face of said standard opposite said first-named face, signal means mounted on said carrier, and means associated with said target means and with said signal means, when said carrier is mounted on said standard, and operable, when said target means is squarely and forcefully struck, to actuate said signal means.

18. The organization of claim 17 in which said last-named means is laterally and axially yieldable.
19. In a device of the character described, a standard, cushioning means on one substantially vertical face of said standard and presenting a plurality of vertically-spaced target areas, guard means associated with each target area and projecting substantially horizontally forwardly beyond said cushioning means above and below each target area, an opening through said standard and cushioning means upon an axis substantially normal to the plane of said one face of said standard and coaxial with the center of each target area, a carrier, means readily removably securing said carrier to that face of said standard opposite said first-named face, said carrier being formed with openings therethrough registering, when said carrier is secured to said standard, with said openings through said standard, signal means carried on said carrier, an element supported on said standard and movable relative thereto to actuate said signal means, a ribbon having one end secured to said carrier at a point above the uppermost of said carrier openings and extending across all of said carrier openings, spring means anchoring the other end of said ribbon to said carrier at a point below the lowermost of said carrier openings and resisting upward movement of said other end of said ribbon, laterally and axially yieldable means located in each of said standard openings, each extending from the center of its associated target area to said ribbon, and means providing an operative connection between the lower end of said ribbon and said element.

20. The organization of claim 16 including a carrier, means readily removably securing said carrier to that face of said standard opposite the first-named face thereof, and in which said carrier is formed with openings registering, when said carrier is secured to said standard, with said openings through said standard, and said rod, bell, clapper, ribbon, spring means, and lever are supported on said carrier.

ROBERT V. FESSLER.
